UNITED STATES PATENT OFFICE

NOBLE L. FELLOWS, OF DETROIT, MICHIGAN, ASSIGNOR TO BARNES SCALE COMPANY, OF DETROIT, MICHIGAN, A CORPORATION OF MICHIGAN

DESIGN FOR A SCALE

Application filed February 6, 1930. Serial No. 34,440. Term of patent 14 years.

To all whom it may concern:

Be it known that I, NOBLE L. FELLOWS, a citizen of the United States, residing at 2842 W. Grand Boulevard, Detroit, in the county of Wayne, and State of Michigan, have invented a new, original, and ornamental Design for a Scale, of which the following is a specification, reference being made to the accompanying drawing, forming part thereof.

The drawing is a perspective view of the scale, showing my new design.

I claim:

The ornamental design for a scale substantially as shown.

NOBLE L. FELLOWS.
